(57) CLAIM

The ornamental design for a planter for a mailbox, as shown and described.

DESCRIPTION

FIG. 1 is a perspective view of a planter for a mailbox; FIG. 2 is a front elevational view thereof; FIG. 3 is a rear elevational view thereof; FIG. 4 is a left side elevational view thereof, the right side elevational view being a mirror image of the left; FIG. 5 is a top plan view thereof; FIG. 6 is a bottom plan view thereof; FIG. 7 is a front elevational view of a second embodiment of my new design comprising a planter for a mailbox, the rear elevational view being a mirror image of the front; FIG. 8 is a top plan view of the second embodiment; FIG. 9 is a bottom plan view thereof; FIG. 10 is a left side elevational view of the second embodiment; FIG. 11 is a right side elevational view thereof; FIG. 12 is a front elevational view of a third embodiment of my new design comprising a planter for a mailbox, the rear elevational view being a mirror image of the front; FIG. 13 is a top plan view of the third embodiment; FIG. 14 is a bottom plan view thereof; FIG. 15 is a left side elevational view of the third embodiment; and, FIG. 16 is a right side elevational view thereof. Portions of the views shown in phantom form no part of the design.
